UNITED STATES PATENT OFFICE.

EMILE ALLIER, OF CHICAGO, ILLINOIS.

DESIGN FOR A SPRAYING-NOZZLE MEMBER.

SPECIFICATION forming part of Design No. 31,408, dated August 15, 1899.
Application filed June 21, 1899. Serial No. 721,384. Term of patent 3½ years.

To all whom it may concern:

Be it known that I, EMILE ALLIER, a citizen of the Republic of France, residing at Chicago, in the county of Cook and State of Illinois, 5 have invented and produced a new and original Design for a Spraying-Nozzle Member, of which the following is a specification, reference being had to the accompanying drawings, forming part thereof.

Figure 1 is a view in side elevation of a spraying-nozzle member, showing my new design. Fig. 2 is a cross-sectional view thereof, taken on line 2 2 of Fig. 1; and Fig. 3 is a longitudinal sectional view taken on line 3 3 of Fig. 2.

As shown in the drawings, the leading or material feature of my design consists of a casing A, having a tubular neck B extend-

ing at right angles therefrom, the opening of the neck or extension B being provided with 20 screw-threads and communicating with the opening of the casing. The sides of the casing are formed with circular flattened portions a, and that portion of the casing opposite the tube or neck B is formed with a longitudinal 25 slot a', extending the entire length of the casing.

Having thus described my invention, what I claim as new, and desire to secure by Letters Patent, is—

The design for a spraying-nozzle member, substantially as herein shown and described.

EMILE ALLIER.
